UNITED STATES PATENT OFFICE.

CARL MCKINLEY, OF WASHINGTON, DISTRICT OF COLUMBIA.

TYPE-WRITING MACHINE.

SPECIFICATION forming part of Letters Patent No. 232,741, dated September 28, 1880.
Application filed July 14, 1880. (No model.)

To all whom it may concern:

Be it known that I, CARL MCKINLEY, a citizen of the United States, residing at Washington, in the District of Columbia, have invented a new and useful Type-Writing Machine, of which the following is a specification.

My invention relates to improvements in type-writing machines in which a laterally and vertically swinging hand lever or key operates by its lateral motion a type-wheel, and by its vertical motion a printing lever or hammer and paper-feeding device; and the objects of my improvements are, first, to produce by very simple means and manipulation 15 a neat and clear print of large or "capital" and small letters, punctuation-marks, numerals, and all other characters and signs used in ordinary writing and printing; second, to effect an instantaneous change in the use of the 20 different kinds of letters, characters, signs, &c., without interruption of the printing process; and, thirdly, to substitute entire groups, classes, or styles of the type used, one for another—as from Roman to Italic, plain to ornamental, Greek to Hebrew, &c.—with such 25 readiness of action as to occasion but trifling delay in the operation of the machine, at the same time that its scope is thereby enlarged to an almost unlimited extent. I attain these 30 objects by the mechanism illustrated in the accompanying drawings, in which—

Figure 1 is a side elevation of my type-writing machine, a part of the platform being broken away in order to expose the mechanism otherwise hidden by it; Fig. 2, a top view of the same; Fig. 3, a bottom view of the same. Fig. 4 is a central longitudinal section of the feeding device. Fig. 5 is a transverse section in the line xx of Fig. 4. Fig. 6 is a 35 top view of a type-shield, as will be explained.

Similar letters refer to similar parts throughout the several views.

A is a platform, supported by legs a or other suitable means. B is an arm fastened to the 45 rear part of the platform, which, by preference, is inclined at an angle of about thirty degrees, in order to facilitate the reading of the printed matter during the printing process. By means of A and B the devices for operating the type-wheel, the printing-hammer, and the feed movement are supported.

To the front part of the platform A a bearing, C, is attached, by means of a vertical pivot, c . (Shown in dotted lines in Fig. 1.) To this bearing a lever, D, is attached, by 55 means of a horizontal pin, d , and thus the said lever may be moved vertically and horizontally.

The lever D may be provided with a button, d' , and a pointer, d'' , at its free end. Below the button a wedge, d^3 , is formed, which fits into similarly-shaped notches e in a sector-plate, E. This plate E swings on two arms, e' , suitably hung to the bottom of the platform A, and a suitable aperture is made in the platform to allow the plate E to swing up and down, as is shown at a' in Figs. 1, 2, and 3. The plate E is held in its normal position by means of springs e^2 , fastened in a suitable way to the platform A. 70

In front of the notches e the letters, punctuation-marks, and other characters to be used are marked to guide the operator, the central notch being left blank to correspond with a similar blank space on the type-wheel, for the 75 purpose of producing the necessary interval or spacing between the words as written or printed in ordinary practice.

The letters of the alphabet, characters, &c., are arranged alternately on either side of such 80 blank space or central notch in the order of the frequency of their respective use, so that those which are most used shall lie nearest to such central notch, and those which are less used at proportionately greater distance and 85 in proper order, as explained. The number of notches in the sector-plate E will somewhat exceed the number of letters of the alphabet, if necessary; but it is intended that each such notch shall represent, say three different types 90 or characters, (the central notch alone excepted, by reason of its specific office,) only one of which can be printed at a time, subject to the will of the operator.

Behind the plate E a plate, F, is provided, 95 which moves in a suitable aperture, a^2 , of the platform A, and is attached to the lever F' of the printing-hammer, and above the said plate F the lever D has a projecting abutment, d^4 , which touches the plate F as soon as the 100 wedge d^3 is seated in one of the notches e . The rear arm of the lever F ends with a turned-

up head, *f*, which may be covered with leather or other suitable material, and which constitutes the printing hammer or head. This printing-hammer stands opposite an oscillating and revolving type-wheel, *G*, which is provided with a number of rows of types of letters and other characters, *g*⁸, three such rows being indicated in the accompanying drawings. The types *g*⁸ may be the same as those used in ordinary printing, and may be inserted in suitable socket-holes in the type-wheel and secured in place by a little solder. Other suitable modes of fastening may, however, be adopted instead of this device.

15 Types of any suitable material, and with or without hardened surfaces, may be used.

The type-wheel, again, may be composed of a number of wheels, each provided with a circular row of suitable notches adapted for the insertion of types, which wheels may be suitably screwed or otherwise fastened together, so as to clamp the types tightly between them; or the type wheel or wheels may be solid and having the letters and characters engraved upon their cylindrical surface.

25 Instead of such type wheel or wheels, as above described, having raised letters and characters, stencils may be used, arranged in a suitable manner upon the wheel *G*. The letters and characters upon this wheel *G* will extend around the surface of the wheel at regular intervals, with suitable spaces between, and in an order corresponding to that of the same letters and characters upon the sector-plate *E*, a blank space 30 being left upon the type-wheel to correspond to the similar blank space upon said sector-plate, for the purpose of producing the proper spacings between words, &c., as already explained.

35 40 On the rear part of the bearing *C* a toothed sector-wheel, *c*', is formed, into which a conical toothed wheel, *g*, is made to gear accurately. This wheel *g* is attached to a shaft, *g*', suitably hung in the arm *B*, which shaft carries the type-wheel *G* by means of a sleeve, *g*². A transverse pin, *g*³, causes the sleeve and the type-wheel attached thereto to revolve with the shaft *g*', while a longitudinal slot, *g*⁴, allows said sleeve and type-wheel to be moved 45 longitudinally upon it.

50 A loose collar, *g*⁵, is placed upon a suitable reduction of the sleeve *g*², and is held there by means of a rigid collar, *g*⁶, so that the collar *g*⁵ may turn on the sleeve without longitudinal movement.

55 Two trunnions, *g*⁷, are provided on the collar *g*⁵, and these trunnions are fitted into the forked head *h* of a connecting-rod, *h*'. This device serves to move the sleeve *g*² longitudinally without hindering it from revolving; and as this is a general and well-known device which is often used in machine-building I have not deemed it necessary to illustrate it by special sketches and detail views.

60 65 The connecting-rod *h*' is attached to the lower arm of a lever, *i*, in the arm *B*, which is

suitably hollowed out to receive the lever and allow it free movement, and to the upper arm of the lever *i* a horizontal slide, *I*, is attached, which is suitably fitted into the upper part of the arm *B*, and is provided with a handle, *i*', and a stop-lever, *i*². The lever *i*² is pivoted at *i*³ to the slide *I*, and extends forward beyond the slide, and ends with a head, *i*⁴, which is made to enter notches *b* in the bottom of the bearing provided for the slide *I*. A spring, *i*⁵, fastened to said slide, and bearing against the lever *i*², serves to keep the head *i*⁴ in whatever notch it may be placed. These notches *b* correspond to the arrangement of the rows 70 of types *g*⁸ on the type-wheel *G*, and by moving the slide *I* and allowing the head *i*⁴ to enter the first, second, or third notch, *b*, respectively, the first, second, or third row of types is moved into the required position for printing from them, immediately above the printing-hammer *f*, and is held there.

The sleeve *g*² has one rigid bearing in a projection of the overhanging bracket or arm *B*, as at *b*², and may have one removable bearing, *b*³, fastened to the end of the arm *B* by means of a set-screw, *b*⁴. When the bearing *b*³ is removed free access to the type-wheel can be had, and that wheel may be readily removed and another similar wheel, bearing, however, 85 an entirely different set and style of letters, characters, &c., be quickly substituted for it to meet the tastes of the operator or the requirements of his work. This substitution can be effected, as is apparent, without disturbing any other portion of the mechanism.

Upon the rear end of the lever *i*² another lever, *J*, bears, which is pivoted at *j* to the arm *B*, and has a vertical slide, *K*, attached to it by means of a pin, *k*. This slide *K* is fitted into a suitable vertical slot in the arm *B*, and its lower part is forked and has an ink-wheel, *J*', hung to it. A spring, *j*', fastened to the arm *B*, bears upon the slide *K*, and thus causes the lever *J* to be always in contact with the lever *i*². Thus when the lever *i*² is turned upward the ink-wheel *J* is lifted off the type-wheel *G*, and the type-wheel can be shifted longitudinally by means of the slide *I* without clogging the face of the type with ink.

115 An ordinary inking device for supplying ink to the ink-wheel *J*' and suitably distributing the same upon its surface will, in practice, be fastened to the arm *B* and connected with said ink-wheel, or, if it should be deemed necessary or preferable on any account, the ink-wheel and inking device, as above described or referred to, may be discarded altogether and its place and office supplied by the ink band, or ribbon now in general use, which would be 120 suitably attached to the arm *B* in such manner as to bring said ink band or ribbon into the proper position for printing, to wit, above the paper and between the surface of the type-wheel and printing head or hammer.

125 130 Below the type-wheel two rollers, *L L'*, are hung in a suitable frame, *l*, one side of which

frame slides in a groove, a^3 , of the platform A. The center of said frame l consists of a longitudinal rib, l' , with ratchet-teeth l^2 at the bottom. This rib l' slides in a transverse guide-groove, a^4 , formed in the platform, which guide closes around the sides and bottom of the rib l' , with the exception of the bottom on the right side, which is open to the center. The left end of the rib is provided with an arm, m , to which the end of a clock-spring is attached. This clock-spring M is suitably attached to a pin, m' , of a stand, m^2 , on the platform A. The tendency of the spring M to wind itself upon the pin m' serves to pull the frame l from the right to the left, and thus furnishes the power for a self-feed of the paper. This feed is controlled by an escape-lever, M' , suitably hung to the platform A and provided with an angular arm, m^3 , which extends under the lever F' of the printing-hammer, and is held upon said arm by means of a tension-spring, m^4 .

The stroke of the lever F' being greater than that of the escape-lever M' , it follows that the operation of the latter takes place before and after the printing, and the paper is not moved during the act of printing.

Upon the roller L the paper X is rolled, and as it is discharged therefrom to the roller L' it passes under a guide-roller, L^2 , suitably hung to the frame l , and is thus held even with the surface of the platform A. In passing over the roller L' the paper is pressed against it by a roller, L^3 , of elastic material, whereby it is caused to move evenly, and with a slight tension between the rollers L and L' . Each of the said rollers L L' may be provided with a pulley, l^3 , over which a cord, l^4 , is passed, which keeps the rollers in uniform movement and enables the operator to move the paper with either hand by means of a thumb head or button, l^5 , secured to the right end of roller L and to the left end of roller L' . This latter device, which constitutes the transverse feed-motion, serves to locate the paper for the new or next line, when one has been printed, and so on consecutively, and is worked by hand. A dial-plate and pointer or ratchet wheel and pawl may, however, be used in connection with one of the rollers in order to insure accuracy of spacing between the lines of print.

A bar, a^5 , suitably fastened to the platform A by means of screws a^6 , forms the upper part of the groove a^3 , and when the frame l is to be taken out of its bearings this bar a^5 must be first removed.

A type-shield, N, is suitably fastened to the arm B, and extends under the type-wheel G, where it is provided with an aperture, n , sufficiently large to admit of the printing from any required type, while it prevents the neighboring type from being touched by the paper.

Operation: The ink-wheel having been properly supplied with ink, or the ink-ribbon having been placed in position, as described, and a sheet of paper of any width less than the length of the rollers L L' having been prop-

erly and neatly rolled upon L, its free end is passed forward under the guide-roller L^2 and suitably inserted between the rollers $L' L^3$. The operator now moves the frame l to the right, which causes the ratchet-teeth l^2 to slide over the ends of the escape-lever M' and winds the spring M upon the pin m' until the paper is brought into the desired position under the type-wheel for receiving the imprint of the first letter. The operator next moves the lever D into a notch, e , representing the letter or character he desires to print, whereby the corresponding type upon the type-wheel G is brought undermost and into position above the slot n in the type-shield N and above the hammer or printing-head f . The wedge d^3 is now pressed into the notch e , already indicated, and the downward pressure is continued until the notched plate E is depressed as far as possible, whereby the abutment d^4 is caused to press at the same time upon the plate F, which throws the hammer f up against the paper, which, in turn, receives a correct print from the superimposed type, this print being that of the letter or character indicated by the pointer d^2 upon the plate E. The lever D is now lifted above the plate E. This plate and the lever F' resume their normal positions, and the latter in so doing moves the arm m^3 of the escape-lever M downward, whereby the frame l and the paper which it bears are moved to the left the distance of one-half a tooth, l^2 , or of one-half the width between the types g^3 , measuring from center to center. By the next upward movement of the lever F' the arm m^3 is moved up by the spring m^4 , and the position of the escape-lever M is reversed, and thus the frame l is moved to the left the distance, again, of one-half the space between the types, as already explained. It is seen, therefore, that two movements of the escape-lever M take place between the printing of each letter, whereby the distance which the frame l is moved to the left always amounts to the full space between the types g^3 , as is required. In this manner the printing is continued; but when a change of type is required, as from a small letter to a capital letter, or for the purposes of punctuation or insertion of figures, &c., the corresponding row of type on the type-wheel is moved into the necessary position by moving the slide I. This is accomplished by pressing the handle i^4 and stop-lever i^2 together by means of the thumb and forefinger of the left hand, preferably, and moving the slide I until the head i^4 of the lever i^2 stands opposite the corresponding notch b in the arm B. The lever D is then turned opposite the desired auxiliary letter or character marked upon the plate E, and the printing goes on, as before described. If more than an ordinary space is required between two words or sentences, or for the conclusion of a paragraph, &c., the lever D is moved down into the central notch on the plate E as many times in succession as may be required to ef-

fect the desired end, and a blank space will appear on the paper of as many type-widths as there may be movements of the lever.

When letters and characters of different sizes, or styles, or kinds are required to be used the type-wheel is removed by first removing the bearing b^3 , then unscrewing the nut g^{10} and slipping the type-wheel from the sleeve g^2 .

Another type-wheel, with the type desired, is then placed in position upon the sleeve g^2 and secured between the collar g^9 and nut g^{10} , the bearing b^3 is replaced and the printing may be resumed from the point where it was discontinued, or elsewhere.

15 The lever F' may be extended forward under the plate E , as indicated in dotted lines, and be operated by the same, in which case the plate F and the abutment d^4 will be omitted. This modification, however, would not alter 20 the principle or any essential feature of my invention.

Another modification of my type-writer consists in the arrangement of the main parts, so that the arm B , with the shaft g' , shall be at 25 right angles to its position, as indicated in the accompanying drawings, and to the lever D when that lever is at rest in the central notch of the sector-plate E . This modification would require the toothed sector-wheel c' to conform 30 to the changed position of the conical toothed wheel g , and the lever F' to be so changed in direction as to bring the hammer-head f into proper position to conform to the changed position of the type-wheel G . The rear portion 35 of the platform A would also be in the same plane with the front portion, as the inclined position would be no longer desirable. These several rearrangements also, as is apparent, would involve no alteration of the principle 40 of the invention, or of any essential part, but would reduce the machine to somewhat more compact form, and would bring the paper and printed lines nearer to the hand and eye of the operator, as might be preferable in certain cases, not necessary to be specified in this 45 connection.

Having thus described my invention, what I claim, and desire to secure by Letters Patent, is—

50 1. The combination, substantially as hereinbefore set forth, of the horizontally and vertically moving operating-lever, the revolving type-wheel having the circumferentially-arranged types, &c., the shaft with which said type-wheel turns, the gearing connecting said shaft and operating lever, and the printing-hammer actuated by the operating-lever to

press the paper against the type-wheel or inking-ribbon.

2. The combination of the vertically and horizontally moving operating-lever, the bearing C , turning in the platform and provided with a sector-gear, and to which said lever is pivoted to play vertically, the type-wheel supporting-shaft provided with the gear-wheel 65 meshing with said sector-gear, the sleeve reciprocating on and turning with said shaft, the type-wheel fastened on said sleeve, and provided with circumferentially-arranged rows of types, &c., and the printing-hammer actuated by the operating-lever, substantially as and for the purpose hereinbefore set forth.

3. The combination, substantially as hereinbefore set forth, of the platform, the printing-hammer beneath it, the arm overhanging 75 the platform, the type-wheel having the circumferentially-arranged rows of types, &c., the sleeve to which the type-wheel is fastened, the turning-shaft supported by said overhanging arm, and with which the type-wheel sleeve 80 turns while having the capacity of movement endwise thereon, and means, essentially such as described, for sliding said sleeve along its shaft to bring one or other of the rows of types, &c., into the described position relatively to 85 the printing-hammer and secure the type-wheel against accidental endwise movement while admitting of its rotation.

4. The combination of the printing-lever F' , having a spring, m^4 , the spring M , escape-lever 90 M' , having arm m^3 , and the feed-frame l , constructed and operating substantially as set forth.

5. The combination of the notched yielding sector-plate E , the operating-lever D , having 95 an abutment, d^4 , and the printing-lever F' , having abutting-plate F , substantially as and for the purpose set forth.

6. The combination, with the shifting slide I , stop-lever i^2 , and lever J , of the inking-roller, substantially as and for the purpose set forth.

7. The combination of the revolving type-wheel, the vertically and horizontally moving operating-lever, the type-wheel supporting-shaft geared with said lever, the printing-hammer, the vertically-yielding notched sector-plate, and the wedge projection on the operating-lever, whereby turning movement of the type-wheel is guarded against during the action of the hammer, substantially as described.
